CLAIM

We claim the ornamental design for a can opener, as shown and described.

DESCRIPTION

FIG. 1 is a perspective view of a can opener from the front, top and right sides, showing the new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

In the drawings, the broken lines shown in the figures depict unclaimed subject matter and form no part of the claimed design.
